US00D629976S

(12) **United States Design Patent**
Meritt

(10) **Patent No.:** **US D629,976 S**
(45) **Date of Patent:** **** Dec. 28, 2010**

(54) **ANIMAL FEEDER**

(75) Inventor: **Rick Meritt**, Gilmer, TX (US)

(73) Assignee: **Rick Meritt Investments, Ltd.**, Gilmer, TX (US)

(**) Term: **14 Years**

(21) Appl. No.: **29/345,590**

(22) Filed: **Oct. 19, 2009**

Related U.S. Application Data

(63) Continuation of application No. 29/296,682, filed on Oct. 25, 2007, now Pat. No. Des. 602,649, which is a continuation of application No. 11/160,611, filed on Jun. 30, 2005, now Pat. No. 7,370,605, which is a continuation-in-part of application No. 09/920,231, filed on Aug. 1, 2001, now Pat. No. 6,920,841.

(51) **LOC (9) Cl.** **30-03**

(52) **U.S. Cl.** **D30/133**

(58) **Field of Classification Search** D30/133, D30/121, 122, 124, 127, 128, 132; 119/51.01, 119/61, 51.04, 53, 57.91, 54, 53.5, 52.4, 119/51.11, 63, 61.2, 52.1, 57.5, 57.6, 51.13, 119/62, 75, 500, 501; 239/7, 687, 379, 397.5; 222/199, 181.1, 181.2, 185.1, 557, 156, 485, 222/486, 548, 555; 220/200, 227, 247, 262; 221/174, 185.1, 289, 295, 296, 559; 454/35; 209/270, 283, 244; 52/194, 192; 49/279, 49/344, 357; D34/28

(57) **CLAIM**

The ornamental design for an animal feeder, as shown and described.

DESCRIPTION

FIG. 1 is a perspective view of an animal feeder according to my new design;

FIG. 2 is a front elevation view of the animal feeder shown in FIG. 1;

FIG. 3 is a rear elevation view of the animal feeder shown in FIG. 1;

FIG. 4 is a right side elevation view of the animal feeder shown in FIG. 1;

FIG. 5 is a left side elevation view of the animal feeder shown in FIG. 1;

FIG. 6 is a top plan view of the animal feeder shown in FIG. 1; and,

FIG. 7 is a bottom plan view of the animal feeder shown in FIG. 1.

The broken lines are for illustrative purposes only and form no part of the claimed design.

1 Claim, 7 Drawing Sheets
